UNITED STATES PATENT OFFICE.

GEORGE SCHILLER, OF JERSEY CITY, NEW JERSEY, ASSIGNOR TO THE PALM BROTHERS COMPANY, OF NEW YORK, N. Y.

DESIGN FOR AN ARTICLE OF MANUFACTURE.

48,654.

Specification for Design.

Patented Feb. 29, 1916.

Application filed January 3, 1916. Serial No. 70,040. Term of patent 7 years.

To all whom it may concern:

Be it known that I, GEORGE SCHILLER, a citizen of the United States, residing at Jersey City, in the county of Hudson and State of New Jersey, have invented a new, original, and ornamental Design for an Article of Manufacture, of which the following is a specification, reference being had to the accompanying drawing, forming part thereof.

The figure is a plan view of my design to be applied to an article of manufacture.

I claim:

The ornamental design for an article of manufacture, as shown.

GEORGE SCHILLER.

Witnesses:

ALBERT HALL,
BERNARD F. SCHLIE.
